US00D749380S

(12) **United States Design Patent**
Choi et al.

(10) **Patent No.:** US D749,380 S
(45) **Date of Patent:** ** Feb. 16, 2016

(54) **WINE RACK**

(71) Applicant: **Samsung Electronics Co., Ltd.**,
Suwon-Si, Gyeonggi-Do (KR)

(72) Inventors: **EunHa Choi**, Yongin-si (KR); **Sunmin Lee**, Seoul (KR)

(73) Assignee: **Samsung Electronics Co., Ltd.**,
Gyeonggi-Do (KR)

(**) Term: **14 Years**

(21) Appl. No.: **29/456,162**

(22) Filed: **May 29, 2013**

(30) **Foreign Application Priority Data**

Dec. 7, 2012 (KR) 30-2012-0059153

(51) **LOC (10) Cl.** **07-06**

(57) **CLAIM**

The ornamental design for a wine rack, as shown and
described.

DESCRIPTION

FIG. 1 is a top, front, right perspective view of a wine rack
showing our new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another top, front, right perspective view of the wine
rack; and,

FIG. 9 is another top, front, right perspective view thereof.

The broken lines showing bottles in FIG. 8 and refrigerator in
FIG. 9 represent environmental subject matter and form no
part of the claimed design.

1 Claim, 9 Drawing Sheets
